H. HASTINGS.
COMBINED FAN AND ALARM SIGNAL.
APPLICATION FILED SEPT. 9, 1913.

Patented Jan. 15, 1918.

UNITED STATES PATENT OFFICE.

HERBERT HASTINGS, OF BRIGHTON, NEW YORK.

COMBINED FAN AND ALARM SIGNAL.

1,253,488.

Specification of Letters Patent. Patented Jan. 15, 1918.

Application filed September 9, 1913. Serial No. 788,927.

To all whom it may concern:

Be it known that I, HERBERT HASTINGS, a citizen of the United States, residing at Brighton, in the county of Monroe and State 5 of New York, have invented a new and useful Combined Fan and Alarm-Signal, of which the following is a specification.

My invention relates more particularly to fans and alarm signals as may be used on 10 automobiles, the former for directly or indirectly cooling the engine and the latter as an alarm signal to indicate, at the will of the operator, the approach of the automobile, and the objects of my invention are 15 first, to combine these two mechanisms into one unit; second, to utilize the rotation of the fan for vibrating the diaphragm of the signal; third, to obtain greater power than is practical to obtain in the present electric 20 horns and thereby a louder signal or one of more volume of sound; fourth, to provide means for varying the volume of sound at the will of the operator. The objects in the spirit of the invention may be attained in 25 many different arrangements and combination of parts. I show however the constructions and combinations illustrated in the drawing in which—

Figure 1 is a partial sectional view 30 through the axis of a device embodying my invention, by which I show a construction in which the vibrating diaphragm and sound amplifying horn revolve with the fan element.

Fig. 2 is a partial sectional view through the axis of a device embodying my invention by which I show a construction in which the vibrating diaphragm and sound amplifying horn are stationary with respect 40 to the fan element.

Fig. 3 is a view in elevation looking at the front or right hand head of the fan drum of Fig. 2 showing apertures to facilitate the issue of sound from the alarm.

Fig. 4 is a partial view in perspective showing the slotted end of the hollow axle of Fig. 1.

Fig. 5 is a partial view in perspective showing the flattened head end, with teeth 50 thereon, of the vibration-producing element of Fig. 1.

Like numbers refer to like parts in the different views.

In Fig. 1, 1 is the bracket or arm which 55 supports the assemblage, usually between the front of the engine and the rear of the

radiator. This arm is pierced at its upper end to receive the stationary hollow axle 2 which has an enlarged end 2^a slotted transversely at 2^b to receive the flattened head 3^a 60 of the vibrator stem 3 to prevent the latter from turning. The axle 2 is threaded at 2^c and 2^d to receive the nuts 4 and 5 respectively and the lever 6 is also fitted to the threaded end 2^d. The nut 4 serves to draw 65 the bearings of the revolving element into proper adjustment against the head 2^c of the axle and also serves when so adjusted, as a shoulder on the axle which the tightening of the nut 5 draws against the face of 70 the arm 1 thus clamping the axle 2 securely in position on the arm. The lever 6 has an elongated hub portion 6^a which is threaded internally to receive the adjusting screw 7 and the latter is provided with a check nut 75 8 to secure it in adjusted position in the lever. The screw 7 is also threaded internally to receive the threaded end 3^b of the vibrator stem 3. The threads 2^d and 3^b are 80 right and left hand, and as the lever 6 is caused to turn on the threads 2^d of the axle these threads give it axial motion, and since the vibrating stem 3 is held from rotation the threads within the screw 7 engaging with the threads 3^b of the vibrating stem 3 also 85 give this stem axial motion which is the sum of the axial movements caused by the threads within the lever and the threads upon the stem. This axial movement of the vibrator stem is for the purpose of bringing 90 the projecting teeth 3^c provided on the head end thereof into and out of engagement with the projections on the shoe or vibrating block 9^a which in turn is secured to the vibrating diaphragm 9. Supported by suitable 95 bearings on the hollow axle 2 is the fan body 10 which is provided with a belt pulley portion 10^a, a flange 10^b to guide the belt on one side, an offset flange 10^c with the three-fold purpose of guiding the belt on 100 the opposite side, of forming one side of the sound box of the signal and of providing a flange against which the vibratory diaphragm 9 is held by being clamped between it and the flange 11^a of the horn 11 by the 105 screws 12 which also pass through the flange 13^a of the fan blades 13. It will thus be seen that while the fan is rotating the diaphragm of the signal rotates with it but normally out of contact with the vibration 110 producing element except as the latter is brought into contact with the lever

6 and operating this lever more or less will vary the volume of sound by causing the diaphragm to have greater or less vibratory motion.

5 In Fig. 2 the stationary axle 2^e is secured in the supporting arm 1^a by the nut 5^a which is threaded to the end thereof, the tightening of this nut drawing the axle collar 2^x back toward the support, drawing the sound box 14 against the spacing collar 15 which in turn bears against the inner member of the bearing 16 and binds these parts securely against the arm 1^a. The outer member of bearing 16 is mounted in the rotating head 17, to which is secured the vibration producing ring 18 which is provided with projecting teeth 18^a which contact with the pin 19 which is supported in a suitable bearing in box 14 and is normally held out of contact therewith by the expansive pressure of a coil spring which surrounds the small diameter and presses against the shoulder of the head portion 19^a thereof; this pin is projected into contact with the teeth 18^a by pulling the lower end of the lever 20 which is pivoted in suitable bearings on the arm 1^a, to the left which motion forces the central pin 21 to the right and the conical end 21^a thereof forces the wedge pointed contact pin 22 upward between the head 19^a of pin 19 and the bearing projection 23^a of the vibrating shoe 23. The pin 22 is loosely mounted within the collar 2^f of the axle 2^e and is free to vibrate as the pin 19 is caused to vibrate by contact with the teeth 18^a of the ring 18, and by its contact with the bearing projection 23^a transmits the vibration to the vibrating diaphragm 24 to which the shoe 23 is secured; the diaphragm 24 is held at its 40 outer diameter between the flange 14^a of the stationary sound box 14 and the flange 25^a of the amplifying horn 25 by the screws 26. Secured to the flange 17^a of the head 17 is the fan body 27 which is provided with belt flanges 27^a and 27^b, the flange 27^c to which the fan blades 28 are secured and the perforated head portion 27^d with openings E, and the hub 27^f in which is held the outer member of the anti-friction bearing 29 the inner member of which is mounted on the small end of the axle 2^e and on this small end are threaded the check nuts 30 which provide adjustment for proper running condition of the bearings 16 and 29. It will thus be seen

that the sound producing element is normally inoperative and stationary with respect to the revolving fan and vibration producing ring revolving therewith but that contact may be made between the latter and the sound producing element at the will of the operator.

I am aware that prior to my invention alarm signals have been made with vibrating diaphragm and that fans have been made journaled on a stationary axle secured to a supporting arm. I do not therefore claim either of these broadly but I claim

1. In a signal the combination of a revolving fan, a diaphragm mounted on the fan and rotating therewith, means to vibrate said diaphragm consisting of a projection on said diaphragm and a striking device for striking said projection, a spindle on which said fan is mounted to rotate, a stem movable endwise through said spindle, said striking device being carried on the end of said stem and being movable thereby into and out of engagement with the projection on said diaphragm.

2. In a signal, the combination of a tubular support, a horn mounted to rotate about said support, a diaphragm circumferentially supported in said horn, projections on said diaphragm, a stem mounted to move longitudinally through said support to engage with the projections on said diaphragm, and means for moving said stem longitudinally in said support.

3. In a signal, the combination of a tubular support, a fan mounted to rotate about said support, a diaphragm circumferentially supported in said fan, projections on said diaphragm, a stem mounted to move longitudinally through said support to engage with the projections on said diaphragm, and means for moving said stem longitudinally in said support.

4. In a signal, the combination of a tubular support, a horn mounted to rotate about said support, a diaphragm circumferentially supported in said horn, a projection on said diaphragm and a stem mounted to move longitudinally through said support to engage with the projection on said diaphragm.

HERBERT HASTINGS.
